(57) **CLAIM**

The ornamental design for an ultrasonic rangefinder, as
shown and described.

DESCRIPTION

FIG. 1 is a front elevational view of the design;
FIG. 2 is a rear elevational view of the ultrasonic rangefinder
in FIG. 1;

FIG. 3 is a left side elevational view of the ultrasonic
rangefinder in FIG. 1;

FIG. 4 is a right side elevational view of the ultrasonic
rangefinder in FIG. 1;

FIG. 5 is a top plan view of the ultrasonic rangefinder in FIG.
1;

FIG. 6 is a bottom plan view of the ultrasonic rangefinder in
FIG. 1; and,

FIG. 7 is a perspective view of the ultrasonic rangefinder of
FIG. 1.
